UNITED STATES PATENT OFFICE.

GURDY L. AYDELOTTE, OF MIAMI, FLORIDA.

LAND-TORPEDO.

1,276,706.

Specification of Letters Patent. Patented Aug. 27, 1918.

Application filed April 30, 1918. Serial No. 231,782.

To all whom it may concern:

Be it known that I, GURDY L. AYDELOTTE, citizen of the United States, residing at Miami, in the county of Dade and State of Florida, have invented certain new and useful Improvements in Land-Torpedoes, of which the following is a specification.

This invention relates to land torpedoes and it has for its object the provision of an improved device of this character constructed in such manner that it is adapted to burrow its way through the earth for a pre-determined distance and to be exploded at the will of the operator.

Further objects and advantages of the invention will be set forth in the detailed description which now follows:

In the accompanying drawing:

Figure 1 is a side elevation of a land torpedo constructed in accordance with the invention.

Fig. 2 is a partial longitudinal sectional view therethrough, and

Fig. 3 is a vertical section upon line 3—3 of Fig. 2.

Like numerals designate corresponding parts in all of the figures of the drawing.

Referring to the drawing 5 designates a casing within which an electric motor 6 is located. This motor furnishes the power to cause the device to burrow its way through the earth. A plate 7 at the forward end of the motor constitutes a fixed part of a ball bearing which comprises the balls 8 and a rotative ring 9. This rotative ring is secured by screws or other suitable fastening devices 10 to a rotative sleeve 11 located outwardly of the casing 5. The sleeve 11 carries an internal gear 12 with which a

gear wheel 13 meshes. This gear wheel is in turn driven by a pinion 14 on a shaft 15 and this shaft carries a gear wheel 16 that meshes with a pinion 17 mounted upon the main shaft 18 of the motor. It will be seen that this structure constitutes a reduction gearing between the shaft of the motor and the internal gear 12 and that consequently the rotation of the sleeve 11, while much slower than that of the motor shaft is correspondingly more powerful. Threaded at

19 upon the forward end of the sleeve 11 is an auger 20, the threaded connection of this auger with the sleeve 11 rendering it

possible to use augers of varying form. In other words these augers are interchangeable so that an auger of the type suited to the character of the ground may be employed.

The rear end of the sleeve 11 carries a ring 21 which constitutes a rotative part of an anti-friction bearing. Balls 22 are disposed between this ring and a fixed ring 23 which has a fiber center of insulating material indicated at 24. The parts 23 and 24 do not rotate and these parts carry a tail or rudder 25 having an opening 26 formed therethrough for the passage of electric wires of which there are three indicated at 27, 28, and 29. The wires 27 and 28 lead to the motor and the wire 29 has an exposed portion 28^a projecting into a bomb chamber 30 adapted to receive explosives to constitute a bomb. The wire 29 has its terminal end 31 disposed adjacent the exposed portion 28^a of the motor wire and whenever the wire 29 is grounded, current will leap from the point 28^a to the point 31 and explode the bomb. It will be noted that the tail 25 will hold casing 5 and the contained parts against rotation while the sleeve 11 is free to rotate and impart movement to the auger 20. This results in causing the device to burrow its way through the earth until it reaches the point where it is desired to have it explode, whereupon it is only necessary for the operator to ground the wire 29, as before stated, in order to accomplish this result.

Any suitable reel may be employed for paying out the wire, the invention residing more particularly in the torpedo itself, than in the reel, since it is apparent that many ways may be devised for paying out the wires, without departure from the invention.

Having described my invention what I claim is:

1. A device of the character described comprising a contained motor, an auger operated thereby, a bomb carried thereby and a tail for holding the motor against bodily rotation.

2. A device of the character described comprising a casing, a motor contained therein, a bomb therein, a sleeve extending longitudinally over said casing, an auger

- carried by said sleeve and means for imparting movement to said sleeve from the motor.
3. A device of the character described comprising a casing, a motor mounted therein, a bomb therein, an auger, reduction gearing between said auger and the motor and a tail for preventing bodily rotation of the motor.
- 10 4. A device of the character described comprising a casing, a motor mounted therein, a bomb chamber in said casing, a sleeve surrounding said casing and bodily rotative with respect thereto, reduction gearing between the motor and the sleeve, an auger carried by the sleeve and a tail for preventing bodily rotation of the casing.
- 15 5. A structure as recited in claim 4 where-
in said tail is provided with a longitudinally extending channel for the passage of wires 20 and motor wires and wires for creating an electric spark in the bomb chamber disposed in said passage.
6. A device of the character described comprising a casing, a motor mounted there-
in, a bomb chamber in the casing, a sleeve 25 surrounding the casing and rotative with respect thereto, an auger threaded upon said sleeve, an internal gear carried by the sleeve, reduction gearing between said internal 30 gear and the motor shaft and a tail for preventing bodily rotation of the casing.
- In testimony whereof I affix my signature in the presence of two witnesses.
- GURDY L. AYDELOTTE.
- Witnesses:
- JAMES T. SANDERS,
ULY O. THOMPSON.
